AQUARIUM PUMP

Morris R. Gare, 1473 Maple Ave.,
Hillside, N.J. 07205

Filed Nov. 14, 1966, Ser. No. 4,639

Term of patent 14 years

(Cl. D65—1)

FIG. 1

FIG. 2

FIG. 3

FIG. 1 is a side elevational view of an aquarium pump embodying my design;

FIG. 2 is a bottom view thereof, and

FIG. 3 is an end elevational view thereof.

The end opposite to that shown in FIG. 3 is flat and plain.

The dominant features of my design reside in the portions shown in full lines.

I claim:

The ornamental design for an aquarium pump, as shown and described.
